UNITED STATES PATENT OFFICE

2,550,623

ELECTRIC CONTACT BREAKER

Angelo Teruzzi, Milan, Italy

Application January 11, 1947, Serial No. 721,551
In Italy April 13, 1942Section 1, Public Law 690, August 8, 1946
Patent expires April 13, 1962

4 Claims. (Cl. 200—153)

1

This invention relates to electric switches and has special reference to contact makers and breakers, change-over switches and the like.

One important object of this invention is to provide an improved arrangement of the circuit closing elements of such a switch whereby to ensure close engagement between the fixed contacts and the movable contacts of such switches.

A second important object of the present invention is to provide a novel construction of switch wherein a blade or lever carrying the movable contact is floatingly fulcrumed at the end remote from the movable contact.

A third important object of this invention is to provide a novel form of switch having such a floating lever with means whereby the contact end of the lever is moved to bring the contact carried thereby into engagement with a fixed contact and there firmly hold it.

A fourth important object of this invention is to provide a change-over switch having the foregoing characteristics wherein novel arrangements are utilized to prevent closing of both sides of the switch simultaneously.

With the above and other objects in view, as will be presently apparent, the invention consists in general of certain novel details of construction, and combinations of parts hereinafter fully described, illustrated in the accompanying drawings and particularly claimed.

In the drawings like characters of references indicate like parts throughout the views, and:

Fig. 1 is a longitudinal section of a change-over switch constructed in accordance with this invention.

Fig. 2 is a view, partly in section and partly in elevation and showing a lever actuated switch constructed in accordance with the invention.

Fig. 3 is a view similar to Fig. 2, but showing a modification thereof.

Fig. 4 is a view similar to Fig. 2, but showing a second modification thereof.

In the form of the invention shown in Fig. 1, there is disclosed a base B on which is mounted a housing H carrying a cap C. Extending through the center of the base B is a binding post P carrying at its upper end a contact plate 9a whereon is mounted a pair of spaced fixed contacts 9. At each end of the base is shown, at P1 and P2 respectively, a binding post similar to the binding post P. To each of the posts P1 and P2 is attached one end of a C-type leaf spring 13 and the other end of each spring 13 is attached to a lever or blade 8 adjacent one

2

end thereof. Projecting upwardly from the base B are ribs 19a each having a downwardly facing notch 19 which receives a lug 8a formed on the end of the blade 8 adjacent the attachment of the spring 13. The arrangement just described forms, under certain conditions of operation to be presently explained, fulcrum means for the blades 8. At the opposite end of each blade 8 is a contact button 8b forming the movable contacts for engagement with contacts 9. Supported in the housing H are pivot pins 5 and on each of the pins 5 is mounted a rocking lever 4 having on its under side a notch 6. In each notch 6 is mounted the upper end of a push link 7 the lower end of which engages in a V-shaped depression 8c formed at about the center of the blade 8. Beneath each blade 8 is a coiled compression spring 12 which is seated at its lower end in the base B and bears at its upper end against the blade to urge the latter upwardly and thus to normally keep the lug 8a fulcrumed in the notch 19 as shown at the right side of Fig. 1. In one arm of each lever 4 is formed a slot 4a wherein engages a pin 4b carried by a respective pushbutton 1 and 2 extending through the cover C.

In the operation of the device as thus far described the fully open position of the switch is the same at both sides of Fig. 1 as is shown at the right of that figure in which position the lug 8a will fulcrum in the notch 19 and the contacts 8b will be in separated positions. Now let it be supposed it is desired to close contact between lines connected to the binding posts P and P2. The push button 2 is depressed which causes the pin 4b to rock the lever on the fulcrum pin 5. This causes the upper end of the link 7 to swing to the right and primarily effects closing of the left hand contact 8b on the corresponding contact 9. At this instance the pushbutton 2 has not been fully depressed and the upper end of the link 7 still lies to the left of a vertical line through the center of the bottom end of this link. The final movement downwardly of the button 2 swings the upper part of the link 7 to the right of the vertical line and thus beyond the dead center and at the same time frees the lug 8a from the fulcrum surface 19. In order to hold the contacts closed and the lever 4 and link 7 in the position shown at the left of Fig. 4, each of the levers 4 has an arm 4c extending in the opposite direction to the slotted arm and this arm is provided with a lug or boss 4d at its extremity which, with the lever 4 in circuit closing position, engages the slotted bottom end

16 of a centrally disposed push button 3. It will now be seen that upon depression of the button 3 opposite to which it was rocked by depression of the button 2 will first permit fulcruming of the lug 8a in the fulcrum notch 19 and then separation of the contact 8b from the contact 9.

In a change-over switch it is of course undesirable that both sides of the switch should be connected to the center and to prevent such an occurrence in the present switch the following means are used. Alined below the center of the button 3 is a pin 20 on which is rockingly mounted an arm 17 the upper end of which engages in the slotted end 16 of the button 3. The arm 17 has at opposite points of its side edge cam like projections 14 and 15 and the distance between the extreme points of these projections is such that the arm 17 is swung from one side to another as the respective lever 4 is swung to a circuit closing position. When thus one lever 4 is in circuit closing position the lug 4d of the other lever 4 will be engaged by the side of the arm 17 below the camming point. Consequently, as shown at the right of Fig. 1 the button of the open side of the switch cannot be pushed and closing of the open side of the switch cannot be effected.

In the form of the invention shown in Fig. 2 there is provided a base 60 whereon is mounted a pair of spaced binding posts 48 and 58. The post 48 carries a plate 50 whereon is mounted a fixed contact 46. A C-type leaf spring 56 has one end connected to the binding post 58 and its other end connected adjacent one end of a compound blade comprising an upper leaf 40 and a lower leaf 42 firmly pointed together. The leaf 42 carries at one end a lug 41 engaging in the fulcrum notch of a rib 54 which extends upwardly from the base 60. The leaf 40 has a centrally disposed inverted V-shaped bend 43 extending upwardly from the end positions of this leaf. The remaining end of the leaf 42 has a contact 44 fixed thereto and engaging upon closing of the switch on the contact 46. Extending upwardly from the base 60 is a rib 62 in which is rotatably mounted a shaft (not shown) having a square end 34. On the end 34 is fixed a hub 36 from which projects radially a cam 38 the extremity of which is notched as at 37 to receive the apex of the projection 43 upon closing of the switch. The shaft carrying the hub 36 is rotated by a lever 32 provided with a hand knob 30 on its free end. A spring 52 corresponds to spring 12 of Fig. 1. The position of the switch when closed is here shown in full lines and when opened in broken. The operations of closing and biassing of the cam 38 effect the blades, the fixed and movable contacts and the blade fulcrum as in the form shown in Fig. 1.

In the form shown in Figs. 3 and 4 there is provided a base 60a having a transverse grooved portion 60b. This base carries the binding posts 48 and 58. These forms also have the C-type spring 56, coiled spring 52 and arm 59, fixed contact 45 and notched member 54 as in the form shown in Fig. 2.

In the form shown in Fig. 3 there is provided a blade 72 having an upwardly bent camming portion 73 provided at its apex with a depression 73a. This blade has the lug 41 and contact 44 as in Fig. 2. For the operation of the blade in this form there is provided a lever 64 having a journal 68 projecting from its lower end and seated in the groove of the portion 60b. Pro-

jecting from the lever 64 above the blade 72 is a boss 70 which in operation rides along the cam 73 and, upon the switch being closed, seats in the depression 73a. In order to limit swinging movement of the lever, arms 64a project laterally from the upper part of the lever and selectively engage stops 64b carried by the base as the lever moves between the full line switch closing position and the broken line showing of the parts with the switch open position.

In the form shown in Fig. 4 the blade 80 is of the same type as the blade 8 of Fig. 1. The operating lever 64 is like that shown in Fig. 3 except that the boss 70 is replaced by a pin 76 whereon is mounted a hub 74 having an arm 75 projecting tangentially therefrom and having its free end engaging in the bottom of the V-shaped portion of the blade 80. The open and closed positions of the different elements of this form are clearly shown by the broken and full line representations of the moving parts.

Having now particularly described and ascertained the nature of my said invention and in what manner the same is to be performed, I declare that what I claim is:

1. In an electric switch, a fixed contact having means for connection to a conductor, a blade carrying at one end a contact movable into and out of engagement with said fixed contact and having means for connection to a conductor, a fixed fulcrum against which the opposite end of said blade is detachably engaged, a spring engaging the blade intermediate its ends and normally holding the blade in engagement with said fulcrum and said contacts out of engagement, and actuating means operable to move said blade to bring the contact thereon primarily into engagement with the fixed contact and thereafter move said blade out of engagement with said fulcrum.

2. In an electric switch, a fixed contact having means for connection to a conductor, a blade carrying at one end a contact movable into and out of engagement with said fixed contact and having means for connection to a conductor, a fixed fulcrum against which the opposite end of said blade is detachably engaged, a spring engaging the blade intermediate its ends and normally holding the blade in engagement with said fulcrum and said contacts out of engagement, said spring engaging said blade adjacent said fulcrum and spaced from the fulcrum supported end thereof, and operating means operating against said spring and engaging the blade between the location of the spring engagement and the blade supported contact.

3. In an electric switch, a fixed contact having means for connection to a conductor, a blade carrying at one end a contact movable into and out of engagement with said fixed contact and having means for connection to a conductor, a fixed fulcrum against which the opposite end of said blade is detachably engaged, a spring engaging the blade intermediate its ends and normally holding the blade in engagement with said fulcrum and said contacts out of engagement, said spring engaging said blade adjacent said fulcrum and spaced from the fulcrum supported end thereof, and operating means operating against said spring and engaging the blade between the location of the spring engagement and the blade supported contact, said operating means including a rotatable camming arm and means to rotate the same.

4. In an electric switch, a fixed contact hav-

ing means for connection to a conductor, a blade carrying at one end a contact movable into and out of engagement with said fixed contact and having means for connection to a conductor, a fixed fulcrum against which the opposite end of 5 said blade is detachably engaged, a spring engaging the blade intermediate its ends and normally holding the blade in engagement with said fulcrum and said contacts out of engagement, said spring engaging said blade adjacent said fulcrum and spaced from the fulcrum supported end thereof, and operating means operating against said spring and engaging the blade between the location of the spring engagement and the blade supported contact, said operating 10 15

means including a rotatable camming arm and means to rotate the same, said blade having an offset portion wherewith said arm lockingly engages.

ANGELO TERUZZI.
